UNITED STATES PATENT OFFICE.

LEANDER FOUNTAIN ROSS, OF SEARCY, ARKANSAS.

BEDSTEAD-BRACE.

SPECIFICATION forming part of Letters Patent No. 405,603, dated June 18, 1889.

Application filed March 9, 1889. Serial No. 302,681. (No model.)

To all whom it may concern:

Be it known that I, LEANDER FOUNTAIN Ross, a citizen of the United States, residing at Searcy, in the county of White and State 5 of Arkansas, have invented new and useful Improvements in Bedstead-Braces, of which the following is a specification.

The invention relates to improvements in bedstead-braces; and it consists in a certain 10 novel construction and combination of parts, whereby the corner-posts are drawn inward toward the center of the frame to prevent the separation of the side and end rails therefrom.

15 The invention is more fully described hereininafter in connection with the accompanying drawings, and specifically pointed out in the appended claim.

In the drawings, Figure 1 is a plan view of 20 a bedstead provided with a brace embodying the invention. Fig. 2 is a detail view of the tension device.

Referring by letter to the drawings, A designates the frame of the bedstead, which consists of the posts B, the side rails C C, and the ends or heads D D, the extremities of which are attached to the posts. The posts are provided on their inner sides with the inward extending eyes E, and a continuous tightening 25 wire F extends through the said eyes and is connected at its free ends to opposite ends of a plate G, having a central perforation g. This tightening-wire consists of the side portions g' g', which are drawn inward at their 30 centers and connected by the cross-wire H and the end portions g² g², the centers of which are drawn inward and connected by the longitudinal tension-wire K. This tension-wire is connected directly to the center 35 of the end portion g², at the head of the bedstead; but is attached at the other end to the threaded eyebolt L, which extends loosely through the perforation g in the center of the plate G and is engaged on the opposite side 40 thereof by the thumb-nut M. This tension device is preferred because of its simplicity, and being arranged close to the foot-rail of the bedstead it may be tightened by reaching under the latter or by raising the end of 45 the mattress, thus obviating the necessity of removing the latter or otherwise disturbing the bed.

When the thumb-screw is tightened, the end portions of the continuous tightening-wire are drawn inward toward the center of 55 the bedstead-frame, thereby drawing the wire slightly through the eyes E E and tightening the side portions g' g' thereof. Thus the strain on each post is in two directions, caused by the adjacent portions of the side 60 and end portions extending at an angle to each other, and the resultant of these two forces acting in different directions lies midway between them, as indicated by the dotted lines in Fig. 1, and therefore the actual strain 65 on the post is toward the center of the frame.

I am aware that tightening devices and braces have heretofore been used in connection with bedsteads; but they have either necessitated the employment of a number of 70 tightening-wires or a plurality of fastening devices attached to the rails as well as to the legs of the bed or of rings or other connections to render them complete, or else their tensions have been located beneath the center of the bed, where easy access could not 75 be had thereto, or at both ends thereof, where the bed must be moved and two tensions operated instead of one to tighten the frame.

The improved brace comprises but a single 80 side wire, centrally crossed wires, and a tension, and is therefore not only extremely simple and light, but may be readily attached to any bed now on the market by merely inserting the eyes E in the corner-posts. The side 85 wire leading through these eyes connects all four posts and draws them inward toward the center of the frame, thereby preventing displacement in either direction, and all the wires are tightened by adjusting the single 90 tension device, which is located near the foot of the bed, within easy reach of the operator.

I also provide intermediate guide-eyes N N on the side rails, through which the inclined side portions of the tightening-wire pass, 95 thereby preventing sagging and enabling them to bear the superincumbent weight; but these eyes N may be entirely dispensed with, if desired, without detracting from the utility or affecting the operation of my device. 100

Having thus described the invention, I claim—

As a new article of manufacture, the bedstead-tightener herein described, the same

comprising four eyes E, adapted to be screwed into the inner corners of the corner-posts of the bedstead, a single tightening-wire F, rove through said eyes, an apertured plate G, connected at its ends to the ends of said wire and standing adjacent to and parallel with the foot-board D, a cross-wire H, connecting the centers of the side portions g' of said wire, a longitudinal wire K, connected at one end to the center of the head portion g^2 of said wire, a threaded eyebolt L, connected to the other end of said longitudinal wire, its body pass-

ing through the aperture in said plate, and a thumb-nut M, screwed on the outer end of said eyebolt, the whole adapted for use and 15 operation substantially as described.

In testimony that I claim the foregoing as my own I have hereto affixed my signature in presence of two witnesses.

LEANDER FOUNTAIN ROSS.
